CLAIM

The ornamental design for the vehicle component, as shown
and described in the accompanying figures.

DESCRIPTION

FIG. 1 is a front, isometric view of the vehicle component
according to the present design;

FIG. 2 is a top view of the vehicle component of FIG. 1;

FIG. 3 is a right side view of the vehicle component of FIG. 1;

FIG. 4 is a left side view of the vehicle component of FIG. 1;

FIG. 5 is a front view of the vehicle component of FIG. 1;

FIG. 6 is a rear view of the vehicle component of FIG. 1; and,

FIG. 7 is a bottom view of the vehicle component of FIG. 1.

1 Claim, 7 Drawing Sheets

FIG. 2

FIG. 3

FIG. 4

FIG. 5

FIG. 6

FIG. 7
